UNITED STATES PATENT OFFICE.

HERMAN IHLENBURG, OF PHILADELPHIA, PENNSYLVANIA, ASSIGNOR TO
MACKELLAR, SMITHS & JORDAN, OF SAME PLACE.

DESIGN FOR TYPE ORNAMENTS.

SPECIFICATION forming part of Design No. 15,555, dated November 18, 1884.

Application filed September 19, 1884. Term of patent 14 years.

To all whom it may concern:

Be it known that I, HERMAN IHLENBURG, (assignor to MACKELLAR, SMITHS & JORDAN,) of the city and county of Philadelphia, Pennsylvania, have invented and produced a new Design for a Font of Printing-Type, of which the following is a specification.

The nature of my design is clearly shown in the accompanying typographic impression, to which reference is made; and it consists of a series of flourish ornaments, numbered from 1 to 64, to be employed in ornamental typog-

raphy. The impressions are from the types themselves, and show the exact configuration of their faces.

Having now described my invention, I claim as new—

The design for a font of printing-type, substantially as shown and described.

HERMAN IHLENBURG.

In presence of:

C. F. HUEB,

HERMAN METIUS.
